US0D1080632S

(12) **United States Design Patent** (10) Patent No.: **US D1,080,632 S**
(45) Date of Patent: ** Jun. 24, 2025

(54) **LAPTOP SUPPORT DEVICE**

(71) Applicant: **Jianfeng Li**, Ganzhou (CN)

(72) Inventor: **Jianfeng Li**, Ganzhou (CN)

(**) Term: **15 Years**

(21) Appl. No.: **29/987,406**

(22) Filed: **Jan. 23, 2025**

(51) LOC (15) Cl. **14-06**

(52) U.S. Cl.

USPC **D14/447**; D6/406.5

(58) **Field of Classification Search**

CLAIM

The ornamental design for a laptop support device as shown and described.

DESCRIPTION

FIG. 1 is a perspective view of a laptop support device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
